E. GORE.

Churn.

No. 12,127.

Patented Jan. 2, 1855.

UNITED STATES PATENT OFFICE.

EZEKIEL GORE, OF BENNINGTON, VERMONT.

CHURN.

Specification of Letters Patent No. 12,127, dated January 2, 1855.

To all whom it may concern:

Be it known that I, EZEKIEL GORE, of Bennington, county of Bennington, State of Vermont, have invented a new and useful Improvement in Churns; and I do hereby declare that the following is a full, clear, and exact description of the same.

The nature of my improvement consists in perforating the sides of the churn and introducing therein a series of adjustable pins, flattened at their inner extremities, which may be turned by the hand from the exterior of the churn, so as to present a greater or less surface of resistance to the cream, when put in motion by the dasher.

To enable others skilled in the art to make and use my improvement, I will proceed to describe its construction and operation, reference being had to the annexed drawings, making a part of this specification, in which,

Figure 1, is a vertical sectional elevation of my improvement; Fig. 2, a horizontal sectional plan view.

Similar letters of reference indicate corresponding parts in the two figures.

A is the case of the churn, B the dasher spindle, C the floats, D the adjustable pins, E cover, E' bearing of spindle, F ribs.

In the process of churning it is desirable to have some means of producing a ceaseless agitation among the oily globules of butter contained therein, and also of regulating at pleasure the resisting surface presented to the cream.

When the cream to be churned is thin, the resisting surface within the churn should be greater than when it is of a thick consistency, for greater agitation is requisite in the former than in the latter case. In ag-

glomerating or collecting the butter after it has "come" little agitation is desired. By the arrangement of my improved churning, these very important results are effectually obtained.

The pins D, flattened on their inner extremities, pass from the outside of the case (A) of the churn, in toward the center of the churn, as shown in the drawing. They terminate, upon the outside of the churn, in convenient thumb balls, by which they may at all times be adjusted.

It is manifest that the resisting surface

exposed to the moving mass of cream within the churn, will be greater or less according as the flattened ends of the pins D are turned edge wise or side wise. When the cream is thick the pins are turned so that only their edges will oppose the cream. When the latter is thin, then their sides are presented. It is but the work of a moment to adjust the resisting surface to any desired degree. The sides of the churn, within, are also furnished with short ribs, placed at small distances apart. These serve to give additional stability to the bearings of the pins, while their sharp corners offer resistance to the cream and promote agitation. The floats C are so arranged as to move in close proximity to the tops and bottoms of the ribs F, and thus prevent any particles of butter from collecting at the sides of the ribs, above the sweep of the floats. No particular novelty is claimed for the floats in themselves. They are attached to the spindle C in the usual manner.

By means of the invention herein described I am enabled to make a churn at a very trifling cost, which effects the separation of the butter from cream or milk, in a remarkably short period of time, and in the most thorough manner. In the opinion of some individuals, butter, when very quickly, produced, is not of so good a quality, as when longer time is spent in the churning. By means of my adjustable pins, the time of churning may be regulated to suit the pleasure of the operator, with the utmost nicety. The churn may thus also be adjusted to the power at hand for driving it. If only a very small force is convenient it may be made use of, by the proper adjustment of the pins.

Having thus described my invention, I claim

Making the pins D, with their inner ends flat, and so arranging them that they may be turned to the right or left, as desired, and thus made to present a large or small resisting surface to the agitated cream and facilitate or retard the production of butter substantially as set forth.

EZEKIEL GORE.
